UNITED STATES PATENT OFFICE.

ALFRED J. LORIOT, OF NEWARK, NEW JERSEY.

GALLEY.

1,351,295.

Specification of Letters Patent. Patented Aug. 31, 1920.

Application filed January 2, 1919. Serial No. 269,253.

To all whom it may concern:

Be it known that I, ALFRED J. LORIOT, a citizen of the United States, residing at Newark, in the county of Essex, State of New Jersey, have invented certain new and useful Improvements in Galleys; and I do hereby declare the following to be a full, clear, and exact description of the invention, such as will enable others skilled in the art to which it appertains to make and use the same.

This invention relates to printers' equipment and it has for its object to provide a construction that will facilitate the casting of blanks from metal, a plaster of Paris or other material, by reason of the fact that it may be quickly and accurately adjusted to produce a blank of the exact dimensions desired. Thus, in the utilization of the blank in the making up of a form, there is an exact and proper fit and the various annoyances arising from the use of multitudinous and oftentimes misfit furniture, is avoided. A further object of the invention is to provide such a particular structure as will permit of quick and accurate adjustment to the exact size of cast desired, other objects and advantages being apparent from the following description.

In the drawings:

Figure 1 is a perspective view showing a frame embodying the present invention with its parts in position ready to receive a cast, either associated with or independent of "matter".

Fig. 2 is a section on line 2—2 of Fig. 1.

Fig. 3 is a perspective view of the bar that is shown in elevation in Fig. 2, but looking from its other side, being known as the under bar.

Fig. 4 is a sectional view on the line 4—4 of Fig. 1.

Fig. 5 is a section on line 5—5 of Fig. 1.

Fig. 6 is a bottom perspective view of what is known as the over bar, it appearing in elevation in Fig. 1.

Fig. 7 is a top perspective view of one of the filler blocks shown in Figs. 1 and 5, so called because they fill in between the bottom of the frame and the over bar and between the side of the frame and the under bar.

Referring to the drawing, there is shown a bottom plate 10, which is rectangular and may have any thickness necessary to rigidity and the dimensions of which, transversely

and longitudinally, may be such as preferred. This bottom plate is, however, rectangular in the present illustrated embodiment of the invention.

Formed upon or secured to the plate 10 is a rectangular frame including what, for purpose of convenient description, may be termed sides 11 and 12 and upper and lower ends 13 and 14, the inner opposite faces of which are spaced apart across the plate 10, distances that are any desired multiples of typographic unit of measurement, whether such unit be points, picas or some other unit. In the present description the unit employed will be the pica.

The sides and ends are preferably five picas high and four picas wide and in the top faces of them are formed transversely rectangular channels, the channels of the sides being designated 15 while the channels of the ends are designated 16. Each of these channels is one pica wide and one pica deep and they are separated by cross sectional rectangular ribs, each of which is one pica wide and one pica high from the bottoms of the adjacent channels, the ribs of the sides being designated 17 while those of the ends are designated 18. As illustrated the channels and ribs 15 and 17 respectively are parallel at each side and extend crosswise while the channels 16 and ribs 18 at each end are parallel and extend longitudinally and at right angles to those of the sides. It will be noted that the endmost channels 16 are spaced four picas from the extremities of the sides while the endmost channels 15 are spaced four picas from the extremities of the ends so that the outer walls of the outermost channels 16 are flush with the inner faces of the sides while the outer walls of the endmost channels 15 are flush with the inner faces of the ends.

The area of the inclosure of the frame is greater than the "form" ordinarily used and when it is desired to make a simple cast or to make a composite cast smaller than the total area, it is of course necessary to block off that portion of the area that is to be used and it is the desirability of thus blocking off, that induces the present invention.

In connection with the frame above described there is employed a blocking off member that I term the under bar. This under bar is rectangular in cross section and includes a body portion 19 that is equal in height to the maximum height of the wall

of the frame above the base plate 10, which as above stated, is preferably five picas. The length of the body 19 is equal to the distance between the inner faces of the ends 13 and 14 5 so that its extremities 20 may lie snugly thereagainst.

Projecting from each end of the body 19 and overhanging the extremities 20, is a pair 10 of cross sectionally rectangular fingers 21 and 22, of which the fingers 21 are flush with one side face of the body while the fingers 22 are spaced from the finger 21 and from the other side face of the body, a distance of 15 one pica. The fingers are each one pica wide and thus the under bar is four picas wide and five picas high, corresponding to the sides and ends of the frame. Formed transversely of what in use is the outer face of 20 the body 19 are parallel ribs 28, each one pica wide and one pica high, the endmost ribs being flush with the extremities 20 and the intervening channels 29 being one pica wide and one pica deep. The fingers 21 and 22 spring from the endmost ribs 28.

25 In practice the under bar is disposed with its fingers 21 and 22 in channels 16 of the frame ends and with its longitudinal faces spaced from and parallel to the frame sides. By adjusting the bar with its fingers in 30 proper channels it may block off a section of the frame corresponding to the lateral dimension of the cast that is to be made.

When the under bar has been properly positioned for the correct lateral dimension of 35 the cast, it is of course necessary to block off a portion of the space thus blocked off, to give the proper longitudinal dimension. For this purpose a plurality of filler blocks are employed in conjunction with what may 40 be termed an over bar.

The filler blocks are all of the same height and thickness longitudinally of the galley, but may have the same or different widths, the width in each instance being a multiple 45 of picas. One of these filler blocks is shown in perspective in Fig. 7 and to correspond to the dimensions of other parts already given, is five picas high, is five picas wide and its third dimension or thickness is four picas. 50 Thus when in place and resting upon the base plate 10, its outer face is flush with those of the frame and the under bar. The upper end face of the filler block is provided with a pair of transverse rectangular parallel ribs 23 and 24, each one pica wide and one pica high, the rib 23 being flush with the lower face of the body 25 of the block while the rib 24 is spaced one pica from the rib 23 and one pica from the upper face of 55 the body, with a resultant channel 26 and shoulder 27. If then this filler block be disposed between the side 11 and the under bar, its ribs will align with those of the under bar and with the channels of the side, while 60 its channels will align with those of the under

bar and the ribs of the side and by using the proper number and dimensions of filler blocks, the space between the under bar and side will be completely filled.

To hold the filler blocks in position, there 70 is employed the over bar shown in detail in Fig. 6 and in operative position in Fig. 1. This over bar includes a body 30 having upon its under face the longitudinally extending ribs 31 and 32, of which the rib 31 is flush 75 with the longitudinal side face of the body that is directed toward the end 13 of the galley when in use, as illustrated in Fig. 1 and Fig. 2. The rib 31 is one pica high and one pica wide as is also the rib 32, the 80 ribs being separated by a longitudinal channel 33, one pica wide and one pica deep. The rib 32 is spaced from the corresponding longitudinal side face of the body of the over bar a distance of one pica, with a resultant 85 shoulder or rabbet 34.

The ribs 31 and 32 have a length equal to the distance between the inner faces of the sides 11 and 12 of the frame and are midway between the ends of the over bar. The remaining portions of the over bar have each, parallel spaced ribs 35 and 36 that are each one pica high and one pica wide and separated by a channel 37, one pica wide and one pica deep. The ribs 36 are flush with 95 the longitudinal face of the body in which the rabbet 34 is formed while the ribs 35 are at the ends of the channel 33 and are spaced from the other longitudinal face of the over bar by the rabbets or shoulders 38. 100 The over bar as it is shown in Fig. 6 is in practice, inverted by turning it end for end and is then engaged with its ribs 35 and 36 in channels 15 of the sides of the frame, so that the ribs 32 and 33 engage in channels 105 29 of the under bar and in the channels 26 and shoulder forming rabbets 27 of the filler blocks. The dimensions are such that a rectangular continuously walled inclosure is formed between the side 11, the end 13, the 110 under bar body 19 and the filler block bodies 25.

If a piece of blank furniture is to be cast, the metal, plaster of Paris or other material to be used, is poured into the inclosure and 115 will of course have accurate transverse dimensions in terms of picas. If a composite cast is to be made, that is one comprising "matter" in conjunction with a blank, the "matter" is placed in the desired position 120 within the inclosure and whether it be an individual piece or several pieces, the cast is made to fill the inclosure in conjunction with it, thus producing a composite cast in which the different elements are mutually 125 fixed.

It will of course be understood that the parts of the galley may be adjusted as conditions may dictate. Also, the dimensions of the various parts may be different from 130

those specified and that any suitable material or materials may be used.

What is claimed is:

1. A frame whose sides and ends have transverse channels, a bar therein parallel with the sides and having longitudinal fingers adjustably engaging the channels in the ends, this bar also having transverse channels, and a second bar extending across the frame and the first bar and having longitudinal ribs adjustably engaging their channels.
2. A frame, an under bar within the frame, means for holding it in fixed relation thereto at different distances from a side of the frame, filler blocks between said bar and a side of the frame, an over bar crossing the under bar and frame sides, and means whereby it is removably engaged with the frame, the under bar and the filler blocks for holding the latter at different points in the length of the under bar.
3. A frame, an under bar therein parallel with its sides, means for adjustably connecting its extremities with the ends of the frame, an over bar across the under bar and frame and having longitudinal channels in its lower face, means for adjustably connecting its extremities with the sides of the frame, and filler blocks between said under bar and one frame side and having ribs for engagement with the channels of said over bar.
4. A frame whose sides and ends have

alternating ribs and channels in their upper faces, a bar having longitudinal fingers for engagement with channels in said ends, the bar having transverse ribs and intervening channels in its upper face, filler blocks disposed between the bar and a side of the frame and having ribs and channels mating with those of said bar, and a second bar having ribs and channels in its lower face for engagement with the channels and ribs respectively of the frame, the first bar, and the blocks.

5. A frame having alternating ribs and channels on one face extending diametrically of the frame, a bar having longitudinal fingers for engagement with corresponding channels interchangeably to lock the bar within the frame, said bar having transverse ribs and intervening channels, blocks disposed between the bar and a side of the frame and having ribs and channels at that end corresponding to the ribbed face of said bar and a second bar having longitudinal ribs and channels removably engaged with the channels and ribs respectively of the frame, the first named bar and the filler blocks.

In testimony whereof I affix my signature, in the presence of two witnesses.

ALFRED J. LORIOT.
